DRILLING WEIGHT CONTROL SYSTEM

Alphons G. H. Straatman, The Hague, Netherlands, assignor to Shell Development Company, San Francisco, Calif., a corporation of Delaware

Application April 12, 1950, Serial No. 155,387
In the Netherlands April 21, 1949

5 Claims. (Cl. 254—173)

1

The present invention relates to well drilling control systems by which the drill bit fed into the formation being drilled is controlled in accordance with the weight supported on the bit, and pertains, more particularly, to an improvement over the control apparatus of the type described in United States Patent No. 2,371,953, issued March 20, 1945, to Crake.

During the drilling of a borehole, part of the total weight of a string of well drilling tools is taken up by the bit resting on the bottom of the borehole, while the remainder of said weight is taken up by a hoisting cable through the traveling block from which the drilling tools are suspended. In order to keep the bit pressure constant during the drilling operation, efforts are exerted to maintain the tension on the cable as far as possible constant during drilling by controlling rotation speed of the hoisting drum on which the working part of the cable is wound. Since considerable demands are made on both the stamina and attention of the drilling crew in keeping the cable tension constant when a manually-operated brake drum is employed, devices for automatically controlling the feed of cable forming a hoisting drum have been designed.

The United States Patent No. 2,371,953, to Crake, for instance, discloses a device whereby the weight of the drilling tools is utilized to drive a pump, and the discharge pressure generated by the pump is maintained at a value corresponding to the required pressure of the bit on the bottom of the borehole. To accomplish this effect, the pump is coupled to the hoisting drum of the drilling installation.

Since the feeding of the drill bit generally proceeds with slight jerks resulting from the hoisting drum stopping from time to time, it will be seen that the frictional resistances in the hoisting system vary considerably depending upon whether the system is in motion or at rest. Thus, the frictional resistances existing when the hoisting drum is started from its stationary position are greater than those occurring during the continuous movement of the drum and its associated parts. Consequently, the whole mechanism is not set in motion again until that part of the weight of the drilling tools which is taken up by the cable in the hoisting drum has been increased beyond its predetermined constant value and the pressure on the bit has, therefore, been reduced to the same extent. Thus, it may be seen that a substantially constant bit pressure is not maintained for any period of time by devices of this type.

2

The present invention is broadly based on the principle that in order to maintain the required constant bit pressure when the hoisting drum and its associated parts are set in motion, it is essential to lower slightly the pressure which the pump must generate until motion is started; whereupon this pressure is once more raised to the value at which it is normally maintained.

According to the present invention, the pressure which the pump generates is, therefore, periodically reduced for a short interval, irrespective of the feeding device being at rest or in motion. The duration of this decrease in pressure is so short that it has no effect on the bit pressure to be normally maintained, but is, nevertheless, sufficiently long when the feeding device is at rest to deliver a compensation for the frictional resistances occurring at that time.

It is, therefore, an object of this invention to provide a control system for automatically maintaining a constant pressure or weight on the drill bit, irrespective of the frictional resistances in the hoisting system. The present automatic control system in eliminating variations in pressure caused by the frictional resistances of the hoisting system, increases the bit life and gives a faster rate of penetration of the drill bit into the formation, due to the increased percentage of total drilling time during which the drill bit is engaging the earth formation at the optimum pressure. The present automatic control system likewise yields straighter and better gauge boreholes.

With the above and other objects and advantages in view, the invention has particular relation to certain novel features of construction, operation, and arrangement of parts, an example of which is given in this specification and illustrated in the accompanying drawing wherein:

Figure 1 is a schematic view showing the relation of the control pumps to the hoisting device, derrick and associated drilling equipment.

Figure 2 is a diagrammatic view particularly in cross-section of the control device of the present invention.

Figure 3 is a view in cross-section taken along the line 3—3 of Figure 2.

In Figure 1, a derrick 1 is provided with a crown block 2, a cable 3, with its dead end 3a and working end 3b, and a traveling block 4, from which a swivel 5 and kelly and drilling string 6 are suspended by means of a hook 4a. The installation is devised for use in rotary drilling; however, the rotary table and other parts for rotating the drill string, as well as the portion of

drill string extending underground having a drill bit attached thereto, are not shown, being conventional. The working end of the cable 3b is wound around a hoisting drum 7, which, by means of any suitable power transmission device such as a drive belt or chain 8, is coupled to a displacement pump 9, which is the brake pump and may be of any suitable type. If desired, a speed-multiplying transmission may be interposed between the drum 7 and pump 9.

As the drill string 6 lowered into the borehole during drilling operations, the weight of the drill string, insofar as it is not taken up by the pressure of the bit on the bottom of the hole (weight on the bit), tends to rotate the drum 7 and the displacement pump 9. Consequently, the discharge pressure of the pump is proportional to the suspended weight of the drilling string, frictional resistances of the system being neglected. With the delivery side of the pump 9 closed, the hoisting drum 7 is unable to rotate if there is no leakage from this pump, which leakage, however, practically always occurs to a certain extent. In order to compensate for the pump leakage at all times, an independently driven auxiliary pump 10 is provided, the constant output of which is of sufficient volume to compensate for the leakage. The auxiliary pump 10 may be driven by any suitable motor 10a. The discharge pressure side 12 of the auxiliary pump 10 is connected to the discharge pressure side 13 of the pump 9 through a control device 11, the operation of which is described with reference to Figure 2. This device 11 is designed, apart from maintaining the pump pressure at a predetermined and adjustable value, for periodically reducing the brake pump pressure for a short period.

Figure 2 shows the control device 11 as a unit together with the brake pump 9 and its delivery or discharge conduit 13, as well as the auxiliary pump 10 and its delivery conduit 12. The liquid being discharged from the control device 11, said liquid being no longer under pressure, is returned to both pumps 9 and 10 in parallel through conduit 14, in which a cooler 35 may be located. Any suitable liquid may be employed in this system, such as an oil, for example. For the purpose of controlling the delivery pressure of both pumps 9 and 10, the control device 11 is provided with a regulating slide valve 15, the bottom of which is exposed to the discharge pressure of both pumps 9 and 10 through conduits 12 and 13. The top of valve 15 is subjected to the pressure of a spring 16, which urges the slide-valve downwards, and also to the pressure of a liquid of a lower pressure from conduit 29 hereinafter referred to as "regulating pressure." The position of the regulating slide valve 15 determines the size of the opening of a port 36, through which oil from the delivery pipes can escape to the outlet 14, and, consequently, the magnitude of the delivery pressure from both pumps 9 and 10.

Assuming a constant spring pressure, the delivery pressure of pumps 9 and 10 is determined by the regulating pressure prevailing on the top of the regulating slide-valve 15, which throttles the outlet passage 36. This regulating pressure is, in turn, controlled by means of the slidable piston valve 17 by means of which the space 37 above the regulating valve 15 may be put into communication through conduit 38, either with the space 18, which is under delivery pressure from auxiliary pump 10, or with the space 19, which is at the pump intake or nearly zero pressure. With the piston valve 17 in the central

position (as shown), no communication is effected with either space.

The piston valve 17 forms an integral part with the piston 20 and the piston rod 21 extending upwards. By means of a ball-bearing gland 22 and a lever 23, this compound part or linkage, made up of elements 17—20—21, is subjected to a downward force, which is supplied by variable weights 24 and an adjustable spring 25. When the piston 20 is in a position of equilibrium, this downward force balances the upward force exerted by the delivery pressure in space 18 so that this delivery pressure can be adjusted by varying the weights 24 and the tension of the spring 25. If, for some reason, the combined delivery pressure from pumps 9 and 10 becomes temporarily higher than the force applied by the lever 23, the piston 20 and the piston valve 17 rise, the space 37 above the regulating valve 15 is brought into communication with conduits 28 and 38, space 18, conduit 38 and the outlet pipe 14. The pressure in space 37 will, therefore, decrease. Due to the decrease in pressure in space 37, the regulating valve 15 rises, the outlet port 36 opens and the delivery pressure from pump 10 decreases until the piston 20 is once more in a state of equilibrium. In the case of a decrease in the delivery pressure, the opposite sequence of operations takes place in the control device 11.

In order to reduce the resistance of the piston 20 to movement in an axial direction as much as possible, piston 20 is preferably rotated in any suitable manner, e. g., by means of the hydraulic motor 26, which is driven by the liquid from the auxiliary pump 10. The rotatable piston rod 21 is connected by suitable linkage members 40 and 41 to cylindrical rotary slide valve 27. The linkage comprises an arm 40 having one end fixedly secured to the piston rod 21. The other end of the arm 40 is fitted in a vertical slot 41 in the inner wall of the rotary valve 27. Thus, as arm 40 rises and falls with piston rod 21, it will slide up or down in the slot 41 without being disengaged therefrom.

The rotary slide valve 27 is rotated together with the piston 20 by the motor 26, the rotary slide valve 27 being provided with an orifice or orifices 28, which momentarily register with one end of conduit 29, connected to the liquid-filled space 37 above the regulating valve 15. When, during the rotation of valve 27, the orifice 28 registers with conduit 29, a small quantity of the liquid escapes through the port 42 and the passage 43 in the piston 20 and the valve 17, thence through chamber 19 and conduit 38 in the outlet pipe 14. This results in the regulating valve 15 rising a short distance and the pressure under this valve decreasing slightly, owing to the enlargement of the outlet port 36. Thus, the pump 9, if it is not in operation at that moment, develops a tendency to start up, enabling it to overcome the static frictional resistances in the system comprising the pump, the drilling tools and intermediate parts. As soon as conduit 29 is opened, it is closed again by the rotary slide valve 27 and the downward displacement of the piston 20 and the piston valve 17 caused by the decrease in delivery pressure from pump 10, results in a flow of oil to the space 37 above the regulating valve 15, until the original condition has been restored.

In this manner, the control device produces short impulses which are of sufficient magnitude to overcome, on the one hand, any static resistances in the feeding system, but, on the other

hand, have no effect on the nominal bit pressure to be maintained. The quantity of liquid leakink away each time through conduit 29 can be regulated by means of a normally open regulating valve 30, while the number of impulses per unit of time can be regulated by varying the number of revolutions of the hydraulic motor 26, e. g., by means of a by-pass with regulating valve 45. Instead of having only one opening 28, the rotary slide valve 26 may be designed with a number of openings. In addition, a normally open valve 31 is incorporated in the conduit leading from the brake pump 9, while parallel to this conduit there may be provided a by-pass with a non-return valve 32. With valve 31 in the closed position, it is possible to use the pump 9 as a motor by utilizing the liquid supplied by pump 10 and so withdraw the drilling tools from the well. Use can also be made of valve 31 when the control device requires adjustment.

The invention claimed is:

1. A speed-control system for a cable drum driven by the weight of a drill string supported thereby, said control system comprising a first pump driven by the rotation of said drum, a second pump, a prime mover for the second pump, a closed fluid circuit, the high pressure side of said circuit being connected to the exhaust sides of said pumps in parallel and the low pressure side of said circuit being connected to the intake sides of said pumps in parallel, variable orifice valve means connected in said circuit between the high and the low sides thereof to maintain a back pressure on the first pump opposing the weight responsive rotation of said drum, weighted pilot valve means responsive to increases and decreases of pressure on the high side of said circuit for increasing and decreasing the orifice of said first valve means, and means continuously actuating said pilot valve for periodically increasing said orifice by small amounts.

2. A speed-control system for a cable drum driven by the weight of a drill string supported thereby, said control system comprising a first pump driven by the rotation of said drum, a second pump, a prime mover for the second pump, a closed fluid circuit, the high pressure side of said circuit being connected to the exhaust sides of said pumps in parallel and the low pressure side of said circuit being connected to the intake sides of said pumps in parallel, pressure-fluid actuated variable-orifice valve means connected in said circuit between the high and the low sides thereof to maintain a back pressure on the first pump opposing the weight responsive rotation of said drum, weighted pilot valve means responsive to increases and decreases of pressure on the high side of said circuit for increasing and decreasing the fluid pressure actuating said first valve means, third valve means for periodically reducing the fluid pressure actuating said first valve means whereby said orifice is increased by small amounts, and prime mover means continuously actuating said third valve means to effect said periodical pressure reductions.

3. A speed-control system for a cable drum driven by the weight of a drill string supported thereby, said control system comprising a first pump driven by the rotation of said drum, a second pump, a prime mover for the second pump, a closed fluid circuit, the high pressure side of said circuit being connected to the exhaust sides of said pumps in parallel and the low pressure side of said circuit being connected to the intake sides of said pumps in parallel, pressure-fluid operated

variable-orifice valve means connected in said circuit between the high and the low sides thereof to maintain a back pressure on the first pump opposing the weight responsive rotation of said drum, first conduit means forming part of said circuit between the discharge of said second pump and said variable-orifice valve for supplying an operating pressure fluid thereto, second conduit means forming part of said circuit between said variable-orifice valve and the low pressure side of said circuit for discharging operating pressure fluid from said valve, weighted pilot valve means responsive to increases and decreases of pressure on the high side of said circuit for controlling the flow of pressure fluid through said first and second conduit means to and from said first valve means, third valve means in said second conduit means for periodically reducing the pressure fluid to said first valve, fluid motor means for continuously opening and closing said third valve means, and third conduit means between said motor means and said second pump to provide a pressure fluid for operating said motor means.

4. A control system for well-drilling apparatus comprising a rotatable drum, a cable suspending a drill string wound around said drum, whereby said drum is rotatably driven by said string, said control system comprising a first pump driven by the rotation of said drum, a second pump, prime mover means for driving said second pump, intake and discharge ports on said pumps, a pressure fluid control device, conduit means in communication between said control device and the intake and discharge ports of said pumps forming a closed fluid circuit between said pumps and said control device, said second pump being adapted to furnish a supply of pressure fluid for operating said control device and compensating for leakage from said first pump, said pressure fluid control device comprising first valve means in said fluid circuit adapted to throttle the fluid flow therein, thereby maintaining a back pressure on said first pump to oppose the unwinding of said cable from said drum, pilot valve controlling means for the setting of said first valve, means for biasing the pilot valve to maintain the back pressure at a predetermined value, fluid conduit means in communication between said first and second valve means and third valve means in said conduit means for periodically reducing said back pressure by a small amount.

5. A control system for well-drilling apparatus comprising a rotatable drum, a cable suspending a drill string wound around said drum, whereby said drum is rotatably driven by said string, said control system comprising a first pump driven by the rotation of said drum, a second pump, prime mover means for driving said second pump, intake and discharge ports on said pumps, a pressure fluid control device, conduit means in communication between said control device and the intake and discharge ports of said pumps forming a closed fluid circuit between said pumps and said control device, said second pump being adapted to furnish a supply of pressure fluid for operating said control device and compensating for leakage from said first pump, said pressure fluid control device comprising fluid-operated first valve means in said fluid circuit adapted to throttle the fluid flow from said pumps, thereby maintaining a back pressure on said first pump to oppose the unwinding of said cable from said drum, first conduit means forming part of said circuit in communication between the discharge port of said second pump and the low pressure

side of said first valve means, second conduit means forming part of said circuit in communication between the discharge port from the control device and the low pressure side of the first valve means, second valve means in said first and second conduit means for controlling the flow to and from the low pressure side of said first valve means, spring means in said first valve means acting against the low pressure side thereof, means biasing the second valve means to maintain the back pressure at a predetermined value, and third valve means in said second conduit means for

periodically reducing said back pressure by a small amount.
